ATTORNEY.

UNITED STATES PATENT OFFICE.

FRANK J. ROWSE, OF PAWTUCKET, RHODE ISLAND.

PACKAGE FOR VENDING MACHINES.

Application filed January 2, 1925. Serial No. 118.

In coin operated vending machines for vending small packages, one at a time, the packages are placed one on top of the other in a hopper in the machine and are fed down by gravity, as the bottom package is removed and delivered to the buyer. Such packages usually have tightly closed ends, they are generally comparatively thin in proportion to their size, and it is necessary for the delivery mechanism of the vending machine to remove the bottom package and deliver it to the purchaser without injury to the package or its contents and without disturbing or injuring the following package.

The package grasping members of such mechanisms have heretofore been constructed to have grasping members which grab over and onto each end of the bottom package and in practice it has been found extremely difficult to construct such a package delivery mechanism so that it will operate to invariably deliver the bottom package without disturbing the next upper package and without injury to either package and this is even more so where the packages vary in thickness.

The object of my invention is to improve the construction of wrapped packages for vending machines, whereby such packages are positively and invariably delivered, one at a time, to the buyer, without injury to the package and without injuring or disturbing the next following package, in the vending machine.

My invention consists in the peculiar and novel construction of a wrapped package for vending machines, said vending machine package having details of construction, as will be more fully set forth hereinafter and claimed.

Figure 1 is a perspective view of my improved open end package for vending machines.

Figure 2 is a longitudinal sectional view through the package, showing the open ends of the package and also showing part of the package delivery mechanism of a package vending machine adapted to deliver my improved vending machine package, and

Figure 3 is an end view of my improved package for vending machines.

In the drawing 4 indicates my improved package for vending machines and 5 part of a package delivery mechanism of a vending

machine shown to illustrate the adaptability of my improved vending machine package to such vending machines. 55

My improved vending machine package 4 is preferably in the form of a flat oblong package having a body portion 6, forming 60 the package proper and which is the article to be vended, said package 4 having open ends 7, 7, which form open recesses 8, 8, in the ends of the package, as shown in Figure 2. These open ends 7, 7, are formed on the ends 65 of the package by extending a wrapper 9 around and beyond each end of the package so as to form the recesses 8, 8, in each end of the package. The body portion 6 or article covered by the wrapper 9 may consist of 70 toilet paper, paper towels or anything that would be practical to vend in a vending machine.

The part of a vending machine package delivery mechanism 5 shown in the drawing, 75 consists of a rock shaft 10 to which is pivotally secured package delivery arms 11, 11. These arms 11, 11, have bent fingers 12, 12, on their ends and are operated by cams, not shown, to move the arms 11, 11, in and out 80 from one position to the other, as shown in full lines and broken lines in Figure 2. These arms 11, 11, are nominally in an inward position with the fingers 12, 12 in the open ends 7, 7, of the package and in the position 85 as shown in broken lines in Figure 2. The rock shaft 10 is operated by a coin controlled delivery mechanism, not shown. This delivery mechanism may be of any mechanism that will operate to move the bent fingers 12, 90 12, into the recesses 8, 8, in the ends of a package, then move the package out from under a pile of such packages, then move the package down towards the delivery opening and then move the bent fingers 12, 12, out of 95 the recesses 8, 8, so that the package is released and will fall by gravity, through the delivery opening of the machine.

When a buyer wishes to purchase a wrapped article as described from such a vending machine he first places a coin in the machine and then moves a lever which through the mechanism of the machine, rocks the rock shaft 5, as indicated by the arrow a. As the fingers 12, 12, are now in the open ends of the package and against the forward inside edge of the package, the package is moved forward then out from under the next

following package and then downward, when the arms 11, 11, are operated to move the fingers 12, 12 out of the open ends of the package, which is now delivered by gravity, 5 through an opening in the front of the machine, to the buyer.

I do not confine myself to the shape of the open end package shown, as such an open end package would necessarily conform to 10 the shape of the article to be vended.

Having thus described my invention I claim as new:—

A vending machine package comprising an article to be vended and a wrapper wrapped around the article and extending over oppositely disposed ends of the article and forming open pockets in the ends of the package, the ends of the article forming the bottom of the pockets and the overlapping portions of the wrapper forming the sides of the pockets, 15 for the purpose as described. 20

In testimony whereof, I have signed my name to this specification.

FRANK J. ROWSE.
